UNITED STATES PATENT OFFICE.

WILLIAM LEVY AND WILLIAM A. CHRISTIAN, OF ASHLAND, PENN.

IMPROVEMENT IN REIN-GUARDS.

Specification forming part of Letters Patent No. **154,260**, dated August 18, 1874; application filed July 28, 1874.

To all whom it may concern:

Be it known that we, WILLIAM LEVY and WILLIAM A. CHRISTIAN, of Ashland, in the county of Schuylkill and State of Pennsylvania, have invented a new and Improved Vehicle Rein-Guard; and we do hereby declare that the following is a full, clear, and exact description of the same, reference being had to the accompanying drawing forming a part of this specification, in which—

Figure 1 is a plan view, showing the invention applied to shafts; Fig. 2, the same view, showing the invention applied to a pole or double-tree.

The invention relates to harness; and consists in means whereby the entanglement of driving-reins with single-trees and many other accidents may be effectually prevented.

A represents a pole or pair of shafts having a single-tree or pair of single-trees, B. C is a double-tree or cross-bar to which the single-trees are pivoted in the middle. On this piece we fasten a single or double bracket, D, having a single bow, d, in line with, and a double

bow, d', at right angles to, the end of single-tree. It is thus rendered impossible for the reins to go under the single-tree, while if the king-bolt or either trace should break or become detached the single-tree will not strike the legs or heels of the horse or allow him to make his exit from shafts. The closeness of the guards to the ends of single-tree will also secure the traces from becoming detached while being put on with rivets or bolts. They will also serve as a re-enforcement to the wood-work, and be a guard against splitting.

Having thus described our invention, what we claim as new is—

The combination, with the ends of vehicle single-trees, of the bracket D, having single and double bows d d', as and for the purpose specified.

WILLIAM LEVY.

WILLIAM A. CHRISTIAN.
